UNITED STATES PATENT OFFICE.

FRANK C. HAMILTON, OF NEW YORK, N. Y., ASSIGNOR TO EUREKA PROJECTOR DEVICE CO., INC., OF NEW YORK, N. Y., A CORPORATION OF NEW YORK.

BALANCING MEANS FOR SHUTTERS INTENDED FOR USE WITH MOTION-PICTURE-PROJECTION APPARATUS.

1,210,064.

Specification of Letters Patent. Patented Dec. 26, 1916.

Application filed September 30, 1915. Serial No. 53,234.

To all whom it may concern:

Be it known that I, FRANK C. HAMILTON, a citizen of the United States, residing at New York, in the county of New York and State of New York, have invented certain new and useful Improvements in Balancing Means for Shutters Intended for Use with Motion - Picture - Projection Apparatus, of which the following is a specification.

10 This invention relates to the motion picture art, and concerns itself particularly with improvements in revolving shutters for use in projecting apparatus.

One of the objects of the invention is to provide a shutter in which the usual opaque vanes are replaced by glass sectors, or vanes, which, while transparent, cause a destruction of focus or the diffusion of light rays passing through them, and to arrange for 15 ready and effective assembling of such vanes with the usual revolving shutter shaft of a projecting apparatus. Since for certain reasons it is necessary that one of the vanes be larger and of greater weight than the 20 others, and therefore necessary or advisable to balance said greater mass, I aim to provide conveniently adjustable means for quickly ascertaining and establishing the 25 balance.

30 In the accompanying drawings, which are to be taken as a part of this specification, and in which I have shown a merely preferred form of embodiment of the invention, Figure 1 is a side elevation of a device 35 including my invention; Fig. 2 is a similar view, but with certain parts removed; Fig. 3 is an enlarged view of a portion of the showing of Fig. 1; and Fig. 4 is a 40 sectional view taken on the line 4—4 of Fig. 3.

Similar reference characters refer to similar parts.

The numeral 5 indicates a seat member, provided with a plurality of cut-through 45 seats or slots each of which is intended for dove-tail or interlocking engagement with the coöperant and correspondingly shaped shank of a vane 6.

The seat member is transversely centrally bored at 7 to accommodate a sleeve 8, which is exteriorly threaded adjacent one end at 8^a.

Referring to Fig. 3, the seat member 5 is a generally unitary member except for the

subdivisions thereof marked 5^a, 5^b, 5^c, 5^d, 5^e, 5^f, 5^g, 5^h, and except for the subdivisions 5^a and 5^b. These two last subdivisions are each shown as a solid unit. But the other six subdivisions are each composed of a file of laminae as disclosed most clearly in Fig. 4. Any particular pile may have its mass variously adjusted by removing or replacing any of its laminae; and the various piles are located not only at various radial distances from the center of rotation of the shutter but at various angular distances from the radius of the shutter which includes the center line of the heaviest of the vanes, to wit, here assumed to be the uppermost vane in the drawing; thus providing for the maximum flexibility of adjustment.

A duplicate pair of side shields 9, each of the outline indicated in Fig. 1, are centrally bored so as also to take about the sleeve 8 when said side shields are riveted or bolted to the seat member 5, and maintain said seat member and vanes 6 interlocked, as aforesaid. It will be noted that none of these rivets or bolts 20 pass through any of the vanes. Each vane 6 is thicker in its shank than elsewhere, and the arcuate edges of side shields 9 are inturned against arcuate shoulders one carried on each side of each vane and marking the merging of a vane blade into its shank.

85 A trifurcated flat spring 10 is riveted to one of said side shields as shown best in Fig. 1. This spring 10 has centrally offset therefrom a sleeve 10^a adapted to take about sleeve 8. Sleeve 10^a carries a threaded aperture for a set screw 11; the set screw being spirally adjustable so that its shank may pass through sleeve 8's aperture 8^b and have the tip of the shank forced tight against the usual revolving shutter shaft 12 (Fig. 4) 90 usually found in projecting apparatus. With sleeves 8 and 10^a thus mounted fixedly on shaft 12, the shutter is adjusted against end thrust on said shaft by means of a washer 13 and a nut 14 (Fig. 4). 95

A fillet 15 may be employed as shown.

Each of the vanes 6, instead of being opaque, as usual, is preferably of a transparent material which, when halted predeterminedly transversely of the light rays 105 from the illuminator within the projecting apparatus, diffuses said light rays sufficiently to project onto the usual screen nothing

more than an apparently immobile and even area of illumination. Since, therefore, said vanes 6 may most advantageously be constructed of glass, each preferably being a unitary molded piece, it is obvious that a correct balancing of the shutter, sufficient to cause its center of gravity to approach as closely as possible the center of rotation thereof, is of great importance.

19. Inasmuch as many changes could be made in the above construction, and many apparently widely different embodiments of my invention could be made without departing from the scope thereof, it is intended that 15 all matter contained in the above description or shown in the accompanying drawings shall be interpreted as illustrative and not in a limiting sense. It is also to be understood that the language used in the following claims is intended to cover all the generic and specific features of the invention herein described and all statements of the scope of the invention which, as a matter of language, might be said to fall therebetween.

25. I claim:

1. In a rotatable shutter, a plurality of adjustable piles of laminae, carried by the shutter at various locations all removed from the center of rotation of the shutter, each of said piles being spaced differently from said center of rotation.

2. In a rotatable shutter carrying a plurality of vanes so arranged that the center of gravity of said shutter is removed from the center of rotation thereof, a plurality of adjustable piles of laminae carried by the shutter, at different radial distances from

the center of rotation and at different angular distances from a line joining said two centers.

3. In a rotatable shutter carrying a plurality of vanes so arranged that the center of gravity of said shutter is removed from the center of rotation thereof, an adjustable pile of removable laminae removed from said two centers.

4. In a rotatable shutter carrying a plurality of vanes so arranged that the center of gravity of said shutter is removed from the center of rotation thereof, an adjustable pile of removable laminae removed from said two centers, the pile being built up in a direction parallel with the axis of rotation of the shutter.

5. In a rotatable shutter, a plurality of adjustable piles of laminae, carried by the shutter at various locations all removed from the center of rotation of the shutter, each of said piles being spaced differently from said center of rotation, each pile being built up in a direction parallel with the axis of rotation of the shutters.

6. In a rotatable shutter carrying a plurality of vanes so arranged that the center of gravity of said shutter is removed from the center of rotation thereof, a collection of individually removable weights removed from said two centers.

In testimony whereof I affix my signature in presence of two witnesses.

FRANK C. HAMILTON.
